UNITED STATES PATENT OFFICE

2,367,558

STEAM GENERATOR

John Phillips Badenhausen, Philadelphia, Pa.

Application October 12, 1942, Serial No. 461,674

6 Claims. (Cl. 110—165)

This invention relates to steam generators, and more particularly to the reclamation of combustible materials carried beyond the furnace or combustion chamber of the steam generator. In the operation of modern steam generators at high ratings and particularly in the operation of such steam generators which are provided with water cooled walls and forced draft, a very considerable quantity of solid material is, in many instances, carried beyond the combustion chamber. The solid material carried in the stream of gases passing from the combustion chamber of a steam generator stoker fired with anthracite coal, coke breeze and the like usually contains a considerable quantity of combustible material and the combustible content of this solid material may run from thirty to as high as seventy percent. The failure to burn this combustible material may seriously reduce the efficiency of the steam generator and the collection of this material in the back passes of the steam generator or in other parts of the system may introduce operating difficulties.

Various attempts have heretofore been made to reclaim the unconsumed solid combustible material, but none of these have proven wholly satisfactory. For example, it has been proposed to return the unburned carbonaceous material to the combustion chamber with a relatively large quantity of air. The condition of the solid material, particularly as to size, is such that it is difficult to retain it in the combustion chamber, particularly when introduced with large quantities of air. The quantity of air used, also, interferes with the proper operation of the furnace. It has also been proposed to collect and return the unburned solid materials to the coal bunker for mixing with the fuel and reintroduction into the furnace with the main supply of fuel. Where the unburned carbonaceous material has been added to the fuel in the bunker and introduced therewith, the condition of such material permits of its being picked up and carried away with the furnace gases prior to the completion of the combustion of the combustible content.

It is the principal object of the present invention to provide a steam generator, particularly for burning anthracite coal, coke breeze and the like, with adequate and satisfactory arrangements for reclaiming the unconsumed carbonaceous material carried beyond the combustion chamber.

It is a further object of the present invention to provide a steam generator with adequate arrangements for the collection and transportation

of the unburned carbonaceous material carried beyond the combustion chamber.

It is a further object of the present invention to provide a steam generator for burning anthracite coal with improved arrangements for introducing the unburned carbonaceous material.

It is a further object of the present invention to provide, in a system of the character aforesaid, for the preparation of the unburned carbonaceous material for reintroduction into the combustion chamber.

Other objects of the invention will be apparent from the annexed specification and claims.

The nature and characteristic features of the invention will be more readily understood from the following description, taken in connection with the accompanying drawing forming part hereof, in which:

Figure 1 is a diagrammatic view partly in elevation and partly in vertical section showing a preferred embodiment of the present invention;

Fig. 2 is a fragmentary vertical sectional view through a portion of the apparatus for preparing the material for transport and combustion; and

Fig. 3 is a fragmentary vertical sectional view showing the manner of introduction of the material to be reclaimed into the combustion chamber.

It will, of course, be understood that the description and drawing herein are illustrative merely, and that various modifications and changes may be made in the structure disclosed without departing from the spirit of the invention.

Referring more particularly to the drawing, a steam generator is shown at 10 having a combustion chamber 11, with water cooled walls. The side walls are each lined with a bank of vertical steam generating tubes 12 connected at their lower ends to lower headers 13 for the supply of water thereto and connected at their upper ends to headers 14. The headers 14 are in communication through banks of tubes 15 with a transversely disposed horizontal steam and water drum 16. The front and top wall of the combustion chamber 11 are lined with banks of steam generating tubes 17 which extend from a header 18 to the steam and water drum 16. The rear wall of the combustion chamber 11 may be shaped to form an arch 19 of refractory material supported on and cooled by a bank of steam generating tubes 20 connected to a lower header 21 and to an intermediate header 22. Certain of the tubes 23 extending from the intermediate header 22 to the steam and water drum 16 are exposed to the radiant heat of combustion in

the combustion chamber 11 and aid in supporting and cooling the rear wall of the combustion chamber. It will be noted that the furnace or combustion chamber and the steam generator are integral. A plurality of walls or baffles 24, 25 and 26 are provided to the rear of the baffle at the tubes 23 and spaced to form a plurality of passes for the gases from the combustion chamber 11. One or more of the passes may be provided with banks of steam generating tubes such as the bank of tubes 27 which extends from the header 21 to the steam and water drum 16 and a superheater 28 may also be provided. The rearmost pass may be provided with an economizer 30 connected to the steam and water drum 16.

A coal bunker 35 and a coal hopper 36 are provided for supplying fuel, preferably anthracite coal, to a stoker 37, such as a chain grate stoker, and thereon to the combustion chamber 11. Gates 38 are provided for regulating the quantity of fuel delivered from the hopper 36 onto the chain grate stoker 37. Provision is made at the rear end of the stoker 37 for the discharge of the ash into an ash hopper 39 from whence the same may be disposed of in the customary manner.

The foregoing description of the steam generator is merely by way of illustration as the present invention is applicable to other types of steam generators.

To the rear of the steam generator 10 a dust or cinder collector or separator 40 is provided for separating the unburned solid particles of carbonaceous material from the exhaust gases passing from the steam generator 10. The collector or separator 40 may be of any preferred type suitable for handling furnace gases at high temperature. One such separator is shown in the copending application of Lloyd J. Hersh, filed October 4, 1941, Serial No. 413,603, although any other preferred type may be employed.

The discharge side of the collector 40 is connected to the intake of an induced draft fan 41, the outlet side of the fan 41 being connected in the customary manner to a stack 42. The collecting hopper 43 of the separator 40 is preferably connected to a chamber 45 to which the collected solid carbonaceous material from the hopper 43 is delivered, preferably by gravity.

The collected solid carbonaceous material may be transferred from the chamber 45 in dry form or if desired may be given a suitable treatment by the admixture of fluent materials. If desired fuel oil or a like hydrocarbon containing material may be added to increase the heat value of the material prior to its return to the furnace. Or, if desired other fluent materials, combustible or non-combustible, and including water, which would aid in the transportation of the material to the combustion chamber 11 may be added in quantities such that the mobility of the collected material is increased. For this purpose the chamber 45 may be provided with one or more spray jets 46 for introducing the additive material from a supply pipe 41.

The outlet of the chamber 45 is provided with apparatus for the withdrawal of the collected material, with or without added material. For this purpose a tapered screw 50 is preferably employed for receiving the carbonaceous material and compacting the same. At the same time some additional mixing will be effected if additive materials are introduced. A suitable electric motor 51 is provided for driving the screw 50.

A pipe 52 is connected to the discharge end of the screw 50 for conveying the mobile material

to the combustion chamber 11. The screw 50 serves to force the prepared material along the pipe 52 for further use.

The discharge end of the pipe 52 may be disposed at any desired location in the combustion chamber but preferably extends through one of the gates 38 at the central portion of the front end of the combustion chamber 11 so that the fuel material is delivered into the middle of the bed, that is, intermediate the upper surface of the green coal and the upper surface of the grate 37 at the entrance to the combustion chamber 11.

The mode of operation will now be pointed out.

Coal or other fuel, and particularly anthracite coal or coke breeze is delivered from the bunker 35 through the hopper 36 and onto the grate 37 in the usual manner, the quantity advancing on the grate 37 being controlled by the positioning of the gates 38. The movement of the grate 37 progressively advances the fuel in the customary manner, through an initial ignition zone and a subsequent combustion zone adjacent and under the arch 19, and the ash in a final ash zone is advanced and falls into the ash hopper 39. Air, supplied through the duct 48 passes up through the grate 37 and effects the combustion of the fuel on the grate 37 and the continued combustion of the hot gases arising from the grate 37. The heat from the gases of combustion rising in the combustion chamber 11 and from the burning of the fuel on the grate 37 is available for generating steam in the banks of tubes lining the walls of the combustion chamber 11. The hot gases pass from the combustion chamber 11 and give up further quantities of heat to the water in the tubes 27 connected to the steam and water drum 16 and to the water in the tubes of the economizer 30.

The rising stream of gases from the grate 37 carries with it particles of unconsumed solid material of high combustible content and this material is carried onwardly with the advancing stream of gases and beyond the steam generator 10. The stream of gases with its solids content enters the separator or collector 40 and the solids content is extracted and is collected in the collecting hopper 43. From the collecting hopper 43, the solids pass into the chamber 45. The screw 50 continuously withdraws the collected material from the chamber 45 and compacts the same for delivery. The screw 50 delivers the material through the pipe 52 and into the midportion of the green fuel entering the combustion chamber 11 on the grate 37 and intermediate the upper and lower surfaces of the fuel so that it is not readily carried upwardly with the rising stream of gases. The returned material is blanketed and held for burning by the main stream of fuel supplied to the combustion chamber 11 on the grate 37.

The compaction of the solid unconsumed combustible material permits of the facile delivery of the same and the retention of the same at a location and in a condition for the burning of the combustible constituents. This is effected not only without interference with the proper functioning of the steam generator but in a manner which increases the operative efficiency of the steam generator 10.

When additive materials are employed these are introduced through the spray nozzle 46 and mix with the collected solid material in the chamber 45 with further mixing aided and effected and compaction also effected by the screw 50.

The added material supplied in the chamber

45, particularly if lacking in the lubricating qualities of hydrocarbons, is employed in quantities which will not decrease but preferably increase the mobility of the material upon compaction therewith. The transportation of the material from the chamber 45 and through the pipe 52 will be facilitated if the added material is of a quantity to give with compaction a consistency of mixture capable of flow under pressure through the pipe 52. The mixture is then delivered to the combustion chamber through the pipe 52 in the same manner as the collected dry material.

I claim:

1. In combination with a steam generator having a combustion chamber, a stoker for supplying low volatile fuel in a continuous bed to the combustion chamber for combustion, and means including a conduit for exhausting combustion gases from the combustion chamber, means in said conduit for separating from the exhaust combustion gases solid particles of combustible material carried beyond the steam generator in the exhaust combustion gases, means for compacting the separated combustible material in mobile form, and means including a delivery pipe intermediate the sides of the stoker for supplying said material with the low volatile fuel on the stoker between the upper and lower surfaces of the fuel bed on the stoker, whereby said solid material is retained by the fuel bed for combustion.

2. In combination with a steam generator having a combustion chamber, an endless stoker for supplying low volatile fuel to the combustion chamber and a conduit for exhausting combustion gases from the combustion chamber, a collector in said conduit for collecting solid particles of carbonaceous material carried beyond the combustion chamber in the exhaust combustion gases, a mixing chamber to which the collected solid carbonaceous material is delivered from the collector, means for supplying a mobility increasing agent to said chamber for admixture with said material, and means for compacting said material and for delivering the compacted material to said combustion chamber for introduction with and retention by the fuel supply on said stoker.

3. In combination with a steam generator having a combustion chamber, an endless stoker for supplying low volatile fuel to the combustion chamber, and a conduit for exhausting combustion gases from the combustion chamber, a collector in said conduit for collecting solid carbonaceous material carried beyond the combustion chamber in the exhaust combustion gases, a chamber to which the collected solid carbonaceous material is delivered from the collector, means for supplying water to said chamber for admixture with said material, a screw for compacting said material and advancing the same, and a delivery pipe above said stoker and receiving the compacted material from the screw for

delivering the compacted material for introduction with and retention by the fuel bed on said stoker.

4. In combination with a steam generator having a combustion chamber and a conduit for exhausting combustion gases from the combustion chamber, means in said conduit for separating from the exhaust combustion gases particles of solid combustible material of low volatile content carried beyond the combustion chamber in the combustion gases, a continuously movable endless stoker for supplying low volatile fuel in a continuous bed to the combustion chamber at the bottom thereof for combustion, and means 10 for returning to said combustion chamber said solid combustible material intermediate the upper and lower surfaces of the fuel bed and with the low volatile fuel on said stoker for retention by said fuel, said last means including a delivery 15 pipe extending over said stoker intermediate the sides thereof.

5. In combination with a steam generator having a combustion chamber, a conduit for exhausting combustion gases from the combustion chamber, means in said conduit for separating from the exhaust combustion gases solid particles of combustible material carried beyond the combustion chamber in the combustion gases, a continuously movable stoker of the endless type 20 for supplying low volatile fuel in a continuous bed to the combustion chamber for combustion, means for adding a mobility increasing material to said separated solid combustible material, and means for returning to said combustion chamber said 25 separated combustible material intermediate the upper and lower surfaces of the bed of low volatile fuel supplied by said stoker for retention by said fuel, said last means including a combustible material delivery pipe extending rearwardly over 30 said stoker intermediate the sides thereof.

6. In combination with a steam generator having a combustion chamber and a conduit for exhausting combustion gases from the combustion chamber, means in said conduit for separating from the exhaust combustion gases solid particles of combustible material carried beyond the combustion chamber in the combustion gases, a continuously movable stoker of the endless type 45 for supplying low volatile fuel in a continuous bed to the lower part of the combustion chamber for combustion, means for adding a mobility increasing and volatile supplying material to said separated solid combustible material, means for compacting the separated combustible material, and 50 means for delivering the compacted combustible material and volatile supplying material to the combustion chamber with the fuel bed and intermediate the upper and lower surfaces thereof, said last means including a combustible material delivery pipe extending rearwardly over said 55 stoker intermediate the sides thereof.

JOHN PHILLIPS BADENHAUSEN.
